UNITED STATES PATENT OFFICE.

WILLIAM S. GORTON, OF LONDON, ENGLAND, ASSIGNOR TO WESTERN ELECTRIC COMPANY, INCORPORATED, OF NEW YORK, N. Y., A CORPORATION OF NEW YORK.

ELECTRIC-CURRENT TRANSMISSION.

Application filed January 26, 1923. Serial No. 615,164.

This invention relates to the transmission of electric currents, and aims especially to provide improvements in the two-way transmission of such currents, for instance in the 5 two-way repeating of telephonic currents.

In the particular embodiments of the invention shown in the drawing, this object is accomplished by employing two oppositely pointed one-way electron tube repeaters, an 10 electron tube network individual to each repeater and associated with the input and with the output of the repeater, and a polarized electron tube relay fed from the networks and controlling the potentials 15 of the grids of the repeaters and of certain of the tubes of the networks. Reversal of the pointing of the repeater system occurs only upon the approach toward the repeater system, from the direction to- 20 ward which it is pointed, of power sufficient to cause operation of the polarized electron tube relay through the medium of an electron tube comprised in one of the networks and having its grid and filament con- 25 nected across the line section from which the energy is approaching the repeating system. This operation of the relay controls the grid potentials of the repeaters, to cause the repeater which was last operative to be inop- 30 erative and to cause the other repeater to be operative; and also controls the grid potentials of certain of the tubes of the networks in such a manner that although the current from the output of the operative 35 repeater tends to cause the input voltage of the relay to be such as to again reverse the relay, this tendency is overcome by the tendency of the current incoming into the repeater system to cause the input voltage of 40 the relay to be such as to maintain the new relay setting. When the transmission in the line reverses so as to approach the repeating system from the direction toward which the repeating system is pointed, the last men- 45 tioned tendency is absent, and the current incoming into the repeater system acts, through a tube which is comprised in the network associated with the repeater last operative and which has its grid and filament 50 connected across the line section from which energy is approaching, to cause the sign of the input voltage of the relay to reverse so

that the relay reverses the pointing of the repeating system in a manner similar to that described above. 55

Thus, the invention provides a control effect of a character dependent upon the direction of the transmission in a line by balancing energy of the transmission at the input side of a unilateral element, such as an 60 amplifier, in the line against energy of transmission at the output side of the unilateral element, and utilizes the control effect to control the transmitting efficiency of a transmission path comprising the amplifier. 65 Moreover, the invention provides for two-way repeating without necessitating balancing the impedance of the lines connected to the repeater system to avoid singing of the repeater system due to local circulation of 70 power between the repeater elements, and without involving changes in the continuity or arrangement of the transmission circuits employed, and makes such provision without causing undue distortion of the currents 75 to be repeated and in such manner that when the repeater system has been put in condition to repeat in one direction it remains in such condition until power sufficient to cause reversal of the pointing of the repeater sys- 80 tem approaches the repeater system from that direction. 85

Fig. 1 of the drawing is a circuit diagram of one embodiment of the invention; and Fig. 2 is a diagram of the preferred embodiment, employing push-pull repeaters. 95

R_E and R_W are repeaters for transmitting energy from line W to line E and from line E to line W , respectively, the repeater R_E being coupled to line W by transformer 1 and 90 to line E by transformer 2, and the repeater R_W being coupled to lines E and W by trans- formers 4 and 6, respectively. Associated with the input of repeater R_E is an amplifier 3, and associated with the output of the 95 repeater R_E is an amplifier 5. Similarly, there are associated with the input and with the output of repeater R_W amplifiers 7 and 9, respectively. The plate circuits of amplifiers 3 and 5 include a common resistance 10, and the plate circuits of amplifiers 7 and 9 include a common resistance 11. Each of these four amplifiers 3, 5, 7 and 9, is adjust- 100 ed so as to have zero plate current for zero

input. The gains of these amplifiers are so chosen that the plate current of the amplifier associated with the input of a repeater is always greater than that of the one associated with the output, provided the repeater is transmitting. As a result of this adjustment when energy is flowing through a repeater the direct current in the resistances 10 or 11 common to the plate circuits of the two amplifiers flows in a certain direction. When energy flows into the output of a repeater the direct current in the resistance just referred to is in the opposite direction. The electro-motive forces developed by the direct currents flowing in the resistances 10 and 11 are applied to the input of a polarized vacuum tube relay 12. This relay comprises two three-electrode electron tubes 13 and 14 connected together so that the grid potential of tube 13 is controlled by the plate current of tube 14, and the grid potential of tube 14 is controlled by the plate current of tube 13 in such a manner that an increase of current in the tube 13 makes the grid of the tube 14 more negative than before, thus decreasing the current in the tube 14, which causes an increase of potential on the grid of the tube 13 and thus tends to further increase the current in the tube 13. In a similar manner an increase of current in the tube 14 results in a decrease of current in the tube 13 and consequent tendency to still further increase the current in the tube 14. The device is thus one which is in an unstable condition when the current in the two tubes is the same or nearly the same and is stable only when the current in one tube has increased to a maximum and the current in the other one decreased to a minimum or to zero.

The tubes 13 and 14 may have a high vacuum or may contain a certain amount of gas contributing to their action. The grid, filament, and plate of tube 13 are designated 15, 16, and 17, respectively, and the corresponding elements of tube 14 are designated 18, 19 and 20. The batteries 21 and 22 supply current to the plates of the respective tubes. Current to the plate 17 is carried through a resistance 23, and the drop across a part of this resistance is applied across the grid 18 and filament 19. With current flowing to plate 17, the potential of grid 18 is negative with respect to that of filament 19, and an increase of current to plate 17 makes grid 18 more negative, whereas a decrease of current to plate 17 makes grid 18 less negative, and if the current to plate 17 becomes zero grid 18 assumes the same potential as filament 19 since the current in resistance 23 is in this case zero. In the same manner, the current to plate 20 is supplied through a resistance 24 to one point 25 of which the grid 15 is connected through a circuit comprising elements 26, 27, 28, 11, 29, 30, 31, 32, 10, 33 and 34. This circuit is also the circuit for

applying to the input electrodes 15, 16 of relay 12, the electromotive forces developed as described above by the direct currents flowing in the resistances 10 and 11. Connected with the output of the relay through leads 26 and 35, are two tubes 36 and 37 which control the amplification of the repeaters R_E and R_w and of the amplifiers 3 and 7 associated with their inputs, as described hereinafter. The operation of the relay 12 will now be described somewhat more in detail.

In the normal condition, without any voltage being applied across the leads 26 and 34, the current in one relay tube is much greater than that in the other, and if properly adjusted the current in the latter will be zero. Let us suppose that a current I flows to the plate 17 and that no current is flowing to the plate 20, the negative potential of grid 18 being sufficient to reduce the current in the second tube to zero. Now, if voltage be applied across the leads 26 and 34 in such direction as to make the grid 15 more positive, the current to plate 17 will be slightly increased and grid 18 will be made slightly more negative but there will be no change in the plate current of tube 14, this current being already zero. If, however, voltage be applied to the leads 26 and 34 in the reverse direction so that grid 15 is made more negative, the current to plate 17 will be reduced below the value I , the drop in potential through resistance 23 will accordingly be decreased, grid 18 will be made more nearly positive, a current will flow to the plate 20 which will cause a fall of potential in resistance 24 making grid 15 still more negative, and as a result of this action, if the voltage assumed to be applied to leads 26 and 34 is of sufficient magnitude, the current to plate 20 will exceed that to plate 17, and will cause the current in plate 17 to drop to zero, and a new condition of stability will be established in which the current I will flow to plate 20 and cause the relay 12 to deliver an electromotive force to tubes 36 and 37, but no current will flow to plate 17. This condition will persist until a sufficient positive potential is given to grid 15 by applying voltage in the proper direction to the leads 26 and 34. This system thus operates similarly to an ordinary polarized electromagnetic relay and may for convenience be called a polarized thermionic relay. It is stable in either one of two conditions and unstable under intermediate conditions, and requires a voltage of proper direction and of definite value to throw it from one condition of stability to the other.

The operation of the repeating system will now be described. Consider the repeater to be operative for energy flowing east. In that condition the tube 13 will have a maximum plate current, the tube 14 zero plate current, and the repeater control tubes 36 and 37, 130

maximum plate currents, thus making R_E operative and R_w inoperative since a positive voltage due to drop in resistance 38 in the plate circuit of tube 36 is introduced between the filament and the grid of R_E by means of leads 39 and 40, whereas a negative voltage due to drop in resistance 41 in the plate circuit of tube 37 is introduced between the filament and the grid of R_w by means of leads 42 and 43. The "C" battery 50 of repeater R_E applies to the grid of this repeater a negative potential of such value as to render this repeater inoperative when the potential received from the drop across resistance 38 is zero; but when the repeater control tubes 36 and 37 have their maximum plate currents the potential received by the grid of this repeater due to voltage drop in resistance 38, is sufficient to cause the repeater R_E to operate at such a point on its plate current-grid potential characteristic as to give distortionless amplification, in the manner well known in the art. When the drop across resistance 41 is zero, the "C" battery 51 of repeater R_w applies to the grid of this repeater a negative potential of such value as to cause this repeater to operate at such a point on its plate current-grid potential characteristic as to give distortionless amplification; but when the repeater control tubes 36 and 37 have their maximum plate currents the potential received by the grid of this repeater due to voltage drop in resistance 41 is sufficient to render this repeater inoperative. As long as energy continues to flow east the effect of the amplifier 9 and of the amplifiers 3 and 5, is to maintain R_E operative and R_w inoperative. The amplified output of R_E enters the input of R_w but does nothing there as R_w and its input amplifier 7 are inoperative.

When energy flows west it enters the output of R_E and the input of R_w . The only operative amplifier which it meets is amplifier 5 connected to the output of R_E . The operation of this amplifier causes a reversal of the potential applied to the grid of the tube 13 of the relay 12 and the relay will reverse almost instantly when this potential exceeds a certain definite amount. The reversal of the relay makes R_E inoperative and R_w operative, thus transmitting energy through the repeater to the west.

The grid potentials of R_E and R_w should be so arranged that there is no value of the plate currents of the control tubes 36 and 37 for which both repeaters are operative, so that there will be no time during which both repeaters are operative, and no consequent singing. If singing should occur due to any cause it would probably be of very high frequency and so could be easily stopped by the use of a small amount of reactance which would have very little effect upon the voice

currents. This is the function of the small inductance 55.

It should be noted that the repeater can be reversed while one of the subscribers is speaking if the listener can send the proper amount of energy into the output of the then operative repeater.

Making the repeaters operative and inoperative, as shown in Fig. 1, by variation of the plate currents sends out large impulses of energy upon the lines. This can be obviated by making the repeaters of the push-pull type, as shown at R'_E and R'_w in Fig. 2 which is otherwise like Fig. 1. The use of the push-pull repeaters to avoid the creation of the noise currents is the invention of W. E. Beatty, and is claimed in his Patent, No. 1,470,954, issued October 16, 1923, entitled "Repeating methods and systems", assigned to the assignee of this application.

This repeater requires the application of a certain finite amount of energy before it will reverse itself, but once the energy rises to the proper value, the repeater reverses itself quickly enough to insure that the last portion of the first syllable approaching the repeater from its output side is small, and that the listener has ample opportunity to easily break in on the talker when short pauses occur in the transmission from the talker.

The function of condenser 60, 61, 62 and 63, is to smooth out the current pulses delivered by tubes 3, 4, 7 and 9, respectively, to the resistances 10 and 11. In other words, these condensers cause the fluctuations of voltage across these resistances to be slow.

Similarly, the function of condensers 70 and 71 is to smooth out the voltage pulses delivered to the grid of the tube 13 by the parts of resistances 10 and 11 across which they are respectively connected.

The purpose of resistance 31 is to prevent circulating currents which might flow in the following fashion; consider resistance 38. Starting out from the upper point of that part of the resistance which applies potential to the grids of one of the repeater elements by traversing elements 38, 33, 10, 32, 31, 30, 29, 11, 28 and 27, we arrive at the lower end of the above mentioned portion of resistance 38. Thus, resistances 38, 10 and 11 are inter-connected and any two of these resistances will act as a shunt upon the remaining one. The currents flowing as a consequence of this interconnection are such as to interfere with the proper action of the system. To prevent the circulation of currents through these inter-connections resistance 31 is inserted in the circuit. Resistance 31 should have a value which is high compared with those of the other three resistances mentioned. As a consequence the circulating currents are reduced to negligible

amounts and at the same time the proper functioning of the repeater is not interfered with as connection 30 does not have to transfer any current, but only potentials, in order 5 to control the repeater properly.

The invention is not limited to the details of the disclosure, but is capable of various and widely different embodiments within the spirit and scope of the appended claims.

10 The invention claimed is:

1. A transmission system and two oppositely pointed asymmetrically transmitting channels connected thereto, and means responsive to the transmission in said system

15 for decreasing the transmitting efficiency of one of said channels and for maintaining one of said channels at low transmitting efficiency at the instant when transmission is initially incident upon said channels, said

20 means comprising circuits for balancing the energy of the transmission at one part of the system against the energy of the transmission at another part of the system.

2. A transmission system comprising a

25 line and two oppositely pointed asymmetrically transmitting channels connected thereto, and means responsive to the transmission in said system for controlling the transmitting efficiency of said channels, said means

30 comprising a control element stable in each of two different conditions of operation and unstable in intermediate conditions, for causing one of said channels to have higher efficiency than the other in one of said conditions

35 of stability and causing said other channel to have higher transmitting efficiency than said one channel in said other condition of stability, and said means also comprising circuits for balancing the energy of

40 the transmission at one part of the system against the energy of the transmission at another part of the system and controlling the operation of said element in accordance with the resultant energy.

45 3. A transmitting system comprising two two-way transmitting line sections connected by two oppositely pointed asymmetrically transmitting channels, a control element, stable in each of two different conditions

50 and unstable in intermediate conditions, for causing one of said channels to have a transmitting efficiency higher than that of the other in one of said conditions of stability and causing said other channel to have the

55 higher transmission efficiency in said other condition of stability, and two circuits, both connected to said control element and one connected to one of said line sections and the other connected to said other line section,

60 selectively responsive to opposite directions of alternating current energy flow in said line to cause said control element to have one or the other of said conditions of stability according to the direction of flow

65 of alternating current energy in said line.

4. The method of operating a two-way two channel repeater in a line, which comprises maintaining one of said channels at relatively low transmitting efficiency and the other at relatively high transmitting efficiency during the instant when signals of the direction last transmitted over the line are initially incident upon the repeater, and maintaining said highly efficient channel highly efficient continuously until a cessation of signals approaching the repeater. 75

5. The method of operating a two-way transmitting circuit, an asymmetrically transmitting signaling channel for transmitting signals to said circuit and a separate asymmetrically transmitting signaling channel for transmitting signals from said circuit, which comprises maintaining the channel which last transmitted at relatively high transmitting efficiency and the other channel at relatively low transmitting efficiency continuously whenever neither channel is transmitting. 80

6. In a signaling system, a station comprising a two-way signal transmitting circuit, an asymmetrically transmitting channel for transmitting signals to said circuit, a separate asymmetrically transmitting channel for transmitting signals from said circuit, and means for automatically maintaining the channel which last transmitted at relatively high transmitting efficiency, and the other channel at relatively low transmitting efficiency, continuously whenever neither channel is transmitting. 90

7. The method of operating a signal transmitting station including two signal repeating devices pointed in opposite directions in a transmission system, which comprises maintaining the repeater which last transmitted at relatively high transmitting efficiency and the other at relatively low transmitting efficiency continuously whenever neither repeater is transmitting. 105

8. The method of operating a signal transmitting station including two asymmetrically transmitting space discharge signal repeating devices pointed in opposite directions in a transmission system, which comprises continuously, whenever neither device is transmitting, maintaining for the device which last transmitted the signals a field of force of such value as to permit said device to transmit relatively efficiently, and at the same time maintaining for the other device a field of force competent to maintain the last mentioned device relatively inefficient for transmission. 110

9. A two-way signal transmitting system comprising separate signaling channels for transmitting signals in each direction, a space discharge device in each channel and functioning as an essential element for maintaining efficient transmission therethrough, an electrode in each of said devices, 115

- and means for automatically, continuously when neither device is transmitting, maintaining said electrode of the device which last transmitted the signals at such a potential as to permit said device to transmit at relatively high efficiency, and maintaining said electrode of said other device at such a potential as to maintain the last mentioned device relatively inefficient for transmission.
10. The method of operating an asymmetrically transmitting space discharge signal transmitting device in a signaling line which comprises, after each cessation of transmission of signals through said device, maintaining said device at relatively high transmitting efficiency until reversal of the direction of approach toward said device of signals to be transmitted through said line, and thereupon rendering said device relatively inefficient to transmit, while maintaining the connections of the device to the line.
11. A system comprising a line, repeating means associated therewith, and means for automatically reversing the operative direction of said repeating means with respect to said line without changing its circuital state of continuity with respect to said line, and maintaining said reversed operative direction of the repeating means, after each cessation of transmission, until reversal of the direction of approach toward said repeating means of impulses to be repeated.
12. A two-way transmitting circuit, an asymmetrically transmitting channel for transmitting to said circuit, an asymmetrically transmitting channel for transmitting from said circuit, and means effective, in response to substantially merely initial incidence of the transmission upon one of said channels, to cause one of said channels to have for a time of the order of seconds a transmitting efficiency high relatively to that which it had before said incidence, while permitting the circuit arrangement of said channels and said line to remain unaltered.
13. The method of repeating in a line which comprises, after each cessation of transmission, maintaining the repeating means effective to repeat in the direction in which it last repeated until reversal of the direction of approach toward said repeating means of impulses to be repeated, and thereupon reversing the operative direction of the repeating means while maintaining the connections of the repeating means to the line.
14. The method of operating a two-way transmitting circuit, an asymmetrically transmitting channel for transmitting signals to said circuit and an asymmetrically transmitting channel for transmitting signals from said circuit, which comprises, after each cessation of transmission through said circuit, maintaining the signal channel which last transmitted at a relatively high transmitting efficiency and the other signal channel at a relatively low transmitting efficiency until reversal of the direction of approach toward said channels of the signals to be transmitted through said circuit, and thereupon rendering the highly efficient transmitting channel relatively inefficient for transmitting and the other channel relatively efficient for transmitting, while maintaining the circuit arrangement of said channels and said line unaltered.
15. A signal transmitting system comprising a plurality of circuits having a fixed state of continuity and including a two-way transmitting circuit, an asymmetrically transmitting channel for transmitting signals to said circuit, and an asymmetrically transmitting channel for transmitting signals from said circuit, said system also comprising means for automatically, after each cessation of transmission through said circuit, maintaining the signal channel which last transmitted at a relatively high transmitting efficiency and the other signal channel at a relatively low transmitting efficiency until reversal of the direction of approach toward said channels of the signals to be transmitted through said system, and thereupon rendering the highly efficient channel relatively inefficient and the other channel relatively efficient for transmitting.
16. In signaling apparatus, a station comprising a two-way signal transmitting circuit, a channel including an electron tube for transmitting signals to said circuit, a channel including a second electron tube for transmitting signals from said circuit, means for supplying space current to said tubes, and means for automatically maintaining the direct space current in one of said tubes at zero value and in one at normal operating value, substantially all of the time the station is in condition for use, and maintaining the particular tube which happens to have its space current at normal value at any instant continuously operative until current approaches its output over said circuit.
17. In signaling apparatus, a station comprising a two-way signal transmitting circuit, an asymmetrically transmitting channel pointed in one direction for transmitting signals to said circuit, an asymmetrically transmitting channel oppositely pointed with respect to said circuit for transmitting signals from said circuit, a relay for controlling the transmitting efficiency of one of said channels relatively to that of the other, said relay being stable under two different conditions of operation and unstable in intermediate conditions, and means responsive to the transmission in said channels for causing operation of said relay from one of said conditions of stability to the other.
18. A repeating system comprising two

three-electrode electron tube repeaters in separate paths, the output side of each path being connected to the input side of the other, a three-electrode electron tube associated with the input of one of said repeaters, a second three-electrode electron tube associated with the input of the other repeater, a third electron tube associated with the output of said one repeater, a fourth electron tube associated with the output of said other repeater, an impedance differentially connected in the output circuits of said first and third electron tubes, and impedance differentially connected in the output circuits of said second and fourth electron tubes, said four electron tubes being adjusted to have zero output current for zero input and their gains being so adjusted that whenever an input electron tube and an output electron tube associated with a repeater are both delivering current to one of said impedances the current delivered by the input tube is greater than the current delivered by the output tube, and a vacuum tube relay having its input in circuit with said impedances and having its output connected to supply potentials of one sign to control electrodes of one of said repeaters and its input tube and connected to supply potentials of the opposite sign to control electrodes of the other repeater and its input tube, said relay being stable under two different conditions of voltage input thereto and unstable under intermediate conditions, and being operable from one of said conditions to the other by the application thereto of an input voltage derived from said impedances.

19. The method of operating a two-way two-channel electron tube repeater in a circuit which comprises, substantially all of the time the repeater is in condition for use, maintaining the direct space current of a tube in one of said channels at zero value and of a tube in the other channel at a value corresponding to a distortionless amplification point on the grid potential-plate current characteristic of the tube, and always maintaining the particular tube which happens to have its space current at said point on the tube characteristic at any instant continuously operative until transmission in the system starts or ceases.

20. The method of operating repeating system including a line and a repeater therein having two electron tube signal repeating paths the output of each of which is connected to the input of the other, which comprises maintaining one of said paths at relatively low transmitting efficiency during the instant when signals to be repeated are initially incident upon the repeater, and maintaining on the grid of the repeating tube in the other path, during said instant, a pure direct current control potential, as distin-

guished from the signaling potential, of such value and sign as to render said last mentioned tube relatively efficient for transmitting.

21. The method of operating a repeating system including a line and a repeater therein having two electron tube signal repeating paths the output of each of which is connected to the input of the other, which comprises maintaining one of said paths at relatively low transmitting efficiency during the instant when signals to be repeated are initially incident upon the repeater, and, from said instant until the cessation of signals approaching the repeater; continuously maintaining a pure direct current control potential on the grid of the tube in said other path of such value and sign that the last mentioned tube is relatively efficient for transmitting and that the total voltage variation on said grid is an accurate copy of the signal voltage incoming from the line.

22. A line, a control element associated therewith, and means for operating said control element selectively in accordance with the direction of alternating current energy transmission in said line, said means comprising a closed triangular network having amplifiers in two of the sides of the triangle, and a unilateral device in the third side, one of said amplifiers being in said line, said one amplifier and said unilateral device being pointed in the same direction around said triangle, said two amplifiers having their input circuits at one apex of the triangle, said unilateral device having its input connected to said line and to the output of said one amplifier, and said other amplifier and said unilateral device having their output circuits connected together, and in opposition, to said control element.

23. A transmission system and two oppositely pointed asymmetrically transmitting channels connected thereto, and means responsive to the transmission in said system for decreasing the transmitting efficiency of one of said channels and for maintaining one of said channels at low transmitting efficiency at the instant when transmission is initially incident upon said channels, said means comprising circuits for balancing the energy of the transmission at one part of the system against the energy of the transmission at another part of the system, and said means operating in response to the difference of said energies.

24. In a signaling system, a station comprising a two-way signal transmitting circuit, an asymmetrically transmitting channel for transmitting signals to said circuit, an asymmetrically transmitting channel for transmitting signals from said circuit, and means for automatically maintaining the channel which last transmitted at relatively high transmitting efficiency, and the other

channel at relatively low transmitting efficiency, continuously whenever neither channel is transmitting, said means comprising means for balancing energy of the transmission at one part of the system against energy of the transmission at another part of the system, and said first means operating

in response to the difference of said energies.

In witness whereof, I hereunto subscribe ¹⁰ my name this 12th day of January, A. D. 1923.

WILLIAM S. GORTON.
